UNITED STATES PATENT OFFICE.

JOSEPH LUCCINO, OF RIDGEWOOD, NEW JERSEY, ASSIGNOR TO LUCCINO DAVENPORT COMPANY, OF NEW YORK, N. Y., A CORPORATION OF NEW YORK.

BOX-COUCH.

984,685.

Specification of Letters Patent. Patented Feb. 21, 1911.

Application filed May 28, 1909. Serial No. 498,961.

To all whom it may concern:

Be it known that I, JOSEPH LUCCINO, a subject of the King of Italy, residing in Ridgewood, in the county of Bergen and 5 State of New Jersey, have invented certain new and useful Improvements in Box-Couches, of which the following is a specification.

The present improvement relates to box 10 couches, the object of the invention being to provide an improved box couch having a dust-proof cover separate and independent from the mattress supporting means of the box, but which, however, is operated simultaneously 15 with the shifting of such mattress supporting means, and which latter is so supported that it may be shifted without the necessity of moving the structure from the wall, and to furnish these improvements in 20 a comparatively simple and inexpensive structure.

In the drawings accompanying and forming part of this specification, Figure 1 is an end view of this improved box couch, 25 with the shiftable mattress supporting frame and box cover lifted; Fig. 2 is an end view showing the parts closed on top of the box or storage receptacle; Fig. 3 is a perspective view of the structure partly open; 30 and Fig. 4 is a top view of one end of the structure with parts broken away.

Similar characters of reference indicate corresponding parts throughout the figures of the drawings.

In the embodiment shown the base or body 2 of the structure comprises a storage receptacle or box open throughout the major part of its top, as at 3, and preferably having a part of its top closed, as at 4. Secured 35 to each end, but preferably at a predetermined distance from the rear of the box and preferably at a distance substantially equal to the thickness of the stuffed mattress, is an upright arm or bracket 5 for pivotally supporting the mattress carrying frame 6, which is shown comprising a pair of end members or frames 7 and 8 shown herein of angle formation and comprising a pair of spaced apart cross or horizontal bars 9 and 10 connected at their ends, as at 11 and 12, the latter form of connection being preferably a curved one. The cross bars 10 of the end frames are connected by a series of metallic strips or bars 13 carrying in the present in-

stance a series of spirals 14 for supporting 55 the stuffed mattress 15 which in practice will usually be tied or otherwise secured to the mattress frame so as to be lifted therewith. The storage receptacle is provided with a hinged cover 16 linked by a pair of 60 links 17 to the swinging mattress supporting frame, which, with its stuffed mattress, comprises a couch or bed section. For facilitating the movement of the swinging bed section coil springs 20 are provided, one at 65 each end of the structure, and each having one end secured adjacent to the rear of the mattress supporting frame and its opposite end secured to the end of the box, whereby the lifting of the bed section is made easier. 70 The cover 16 is provided with a flange 21 around its edge to overlap the body of the box in order to make the same dust proof.

From the foregoing it will be observed 75 that the closure for the box is separate and independent of the mattress supporting frame and is held tightly closed upon the box by the weight of the mattress and its supporting frame when in the form of a couch, thus providing a dust-proof receptacle which could even be made air-tight if 80 desired, so that it will be moth-proof as well as dust-proof.

It is, of course, to be understood, that the 85 various details may be more or less modified without departing from the spirit or scope of this improvement. For instance, some other form of stuffed mattress supporting metallic fabric might be used in place of the spirals if preferred.

The box couch is provided with casters 90 25 in the usual manner.

By pivoting the swinging couch section in the manner shown it will be observed that when it is raised into an upright position 95 the stuffed mattress will not project beyond the rear edge of the box and consequently the latter may be opened without moving the couch from the wall, which is, of course, a desirable feature. Moreover, by pivoting 100 the swinging section in the manner shown it permits the weight of the major part of the couch section to rest upon the cover when the structure is in the form of a couch and thus holds the lid or cover tightly closed, 105 and as at this time the metallic strips carrying the spirals rest firmly upon the lid or cover it follows that there is no flexure of

these strips and consequently weight upon the couch will not collapse or pull the end frames toward each other, so that the use of side bars may be entirely done away with 5 when the mattress supporting frame is made up of spirals in the manner shown.

From the foregoing it will also be observed that the structure is not only a dust-proof one, but that all the moving parts 10 and connecting mechanism are located entirely outside of the box, so that the storage receptacle of the latter is not in any way decreased. This also permits the free circulation of air through the mattress supporting 15 frame and prevents the same from becoming musty and dirty as is sometimes the case where parts of this structure are carried within the box.

I claim as my invention:

- 20 1. A box couch comprising a box forming a storage receptacle, a swinging cover hinged to the box and forming a top therefor, a swinging mattress supporting frame pivotally secured to said box independently 25 of the cover, and a connecting member having a fixed point of attachment to the mattress frame and the cover whereby both the mattress frame and the cover may be shifted

simultaneously in the same direction to an upright position to permit access to the box. 30

2. A box couch comprising a box forming a storage receptacle, a swinging cover hinged to the box and forming a top therefor, a swinging mattress supporting frame pivotally secured to said box exteriorly 35 thereof and independently of the cover and at a predetermined distance away from the rear side of the box thereby to permit the mattress to be raised to a perpendicular position without the necessity of moving the 40 box from the wall, a spring or springs connected to the mattress frame and the box exteriorly of the box for facilitating the swinging of the mattress frame, and a connecting member having a fixed point of attachment 45 to the mattress frame and the cover whereby both the mattress frame and the cover may be simultaneously shifted in the same direction to an upright position to permit access to the box. 50

Signed at 9 to 15 Murray st., New York, N. Y., April 29th, 1909.

JOSEPH LUCCINO.
